BUCKLE

Matthew Licursi, Norwalk, Conn.

Application April 1, 1949, Serial No. 84,803

8 Claims. (Cl. 24—180)

1

The present invention relates to a novel buckle, and particularly to a buckle for connecting the ends of a belt.

An object of the invention is to provide a buckle which is easy to operate and will securely hold the free end of the belt in a straight, flat and unbent relation.

Another object is to provide a buckle which presents a pleasing and attractive appearance when in position on a belt.

A further object of the invention is to provide a buckle which is simple in design and which can be easily and cheaply manufactured.

These and other objects are achieved by the buckle of the present invention having a frame and a tongue member which underlies and overlies respectively the apertured end of the belt, with the tongue member having a belt-receiving passage to enable the end of the belt to extend in a flat condition over the frame. The frame is provided with guide means for maintaining the belt in proper position thereon.

The tongue member is secured to the other end of the belt in such a manner that a longitudinal pull on the belt in a direction away from the buckle causes a portion of the tongue member to be moved into engagement with the belt. Either the tongue member or frame member may be provided with a tooth which extends toward the other member and passes into an aperture in the belt to securely hold the belt in adjusted position when the two members are in engagement with the belt.

The two members making up the buckle of the present invention can be easily produced by a simple stamping or forming operation and can be readily assembled, thus enabling the buckle to be made at relatively low cost.

Other features and advantages of the present invention will be apparent from the specification and claims when considered in connection with the drawings in which:

Figure 1 is a plan view of the buckle with the belt shown in dotted lines.

Fig. 2 is a side elevation of the buckle and belt of Fig. 1.

Fig. 3 is a perspective view of the buckle of Fig. 1.

Fig. 4 is a perspective view of another form of buckle of the present invention.

Fig. 5 is a perspective view of still another form of buckle of the present invention.

As shown in the drawings, the buckle 10 of the present invention is employed to adjustably connect the two ends 11, 12 of a belt.

2

The buckle comprises a frame member 13 which is adapted to underlie the end 11 of the belt. The frame member is herein illustrated as having side bars 14 and a transverse portion 15 at its front end.

The frame which may be readily stamped from sheet metal is preferably provided with guide means for maintaining the belt in predetermined relation thereon. The guide means may be formed by connecting the transverse portion 15 to the bars 14 by upstanding walls 16 or 16a as shown in Figs. 3 and 5, or by providing upstanding walls 16a on the bars 14. If desired, the walls 16a may be extended as at 17 over the end to further aid in maintaining the belt in position as shown in Fig. 4 and to provide ornamentation to the buckle.

The tongue member 18 comprises a tongue portion 19 which is adapted to overlie the end 11 of the belt supported by the frame and has a belt-receiving passage 20 at the rear end of the portion 19 and a portion 21 to which the end 12 of the belt is secured.

In accordance with the present invention, the tongue member 18 may be formed from wire stock as shown in Fig. 3, or stamped from sheet metal as shown in Figs. 4 and 5. The tongue portion 22, 22a or 22b may have various shapes as desired.

As shown in the drawings the belt-receiving passage of the tongue member comprises an elongate slot 23, 23a or 23b formed by loops in the wire or a piercing in the stamping at the rear end of the tongue portion and which extends for the full width of the buckle.

The belt-securing portion 21 is formed at the other end of the tongue member from the tongue portion 19 and comprises a loop 24, 24a or 24b through which the end 12 of the belt is passed and the belt secured together, as shown in Fig. 2, by any suitable means.

In the preferred form of the invention the tongue member is bent so that the belt-receiving passage forms a substantial angle to the plane of the tongue portion and the portion for securing the end of a belt to the buckle extends downwardly and rearwardly from the passage portion.

The tongue member is pivotally mounted on the rear end of the frame member in such a manner that the tongue portion overlies the end of the belt supported on the frame member, and the belt-receiving passage is in line with the guide means on the frame member, so that the end 11 of the belt supported on the frame passes thereto through without any substantial bend in the belt.

The belt-securing portion is positioned below the pivot so as to cause the tongue portion to be moved toward the belt end 11 upon a longitudinal pull on belt end 12 in a direction away from the buckle. As herein illustrated this is accomplished by extending the rear ends of bars 14 through the passages 23 and bending them into eyes 14' so as to interlock with the lower walls of the passages to form the pivots about which the tongue member moves.

Either the frame member or the tongue member may be provided with means for interlocking with apertures 25 in the end 11 of the belt to hold the same in adjusted position when the frame member and tongue member are in engagement with the end 11 of the belt. As shown in Figs. 3 and 4, the tongue portion 22, 22a terminates adjacent the portion 15 of the frame member and has a tooth 26, 26a projecting from the end in the direction of the frame member. In Fig. 5 the portion 15 has a tooth 26b projecting upwardly therefrom and the tongue portion 22b extends over the end of the tooth.

In operation, the end 12 of the belt is secured to the tongue member. The end 11 is passed over the frame member and through the passage. As the end 11 is so positioned a pull on the end 12 away from the buckle will cause the tongue portion to move the tooth 26 into an aperture in the belt as shown in Fig. 1. In the form of the invention shown in Fig. 5, the pressure of tongue portion 22b on the top of the belt will cause tooth 26b to enter the aperture in the belt and will prevent the belt from disengaging the tooth.

In all forms of the invention the end of the belt will be flat in the buckle as shown in Fig. 1. This, together with the relation of the tongue member to the frame member, will produce an attractive and pleasing appearance.

Since the parts of the buckle can be easily formed of wire stock or sheet metal and readily assembled, a reasonable cost of manufacture is provided.

Variations and modifications may be made within the scope of this invention and portions of the improvements may be used without others.

I claim:

1. A belt buckle comprising a frame member adapted to underlie the apertured end of a belt and having belt guides to engage the sides of the belt to maintain the belt in position thereon; a tongue member pivotally mounted intermediate its ends on the back end of the frame and having a tongue portion to overlie the belt supported on the frame and having a transversely extending loop forming a belt-receiving passage at the rear end of the tongue portion and in line with the belt guides to receive the belt supported on the frame with a portion of said loop forming the pivot for mounting the tongue member on the frame and having a second belt-securing loop at the rear end of the tongue member to which the other end of the belt is secured, said loop being positioned on the side of the pivotal mounting opposite the tongue portion and at an angle to the plane of the tongue portion, the tongue moving about the pivotal mounting in the direction of the belt upon a longitudinal pull on the secured end in a direction away from the buckle; and a belt-engaging tooth carried by one of the members and adapted to pass through an aperture in the belt and hold the belt when the tongue portion and frame engage the apertured end of the belt.

2. A belt buckle comprising a frame member adapted to underlie the apertured end of a belt

and having belt guides at each side thereof to extend up and over the belt; a tongue member pivotally mounted intermediate its ends on the back end of the frame and having a tongue portion to overlie the belt supported on the frame and having a transversely extending loop forming a belt-receiving passage at the rear end of the tongue portion and in line with the belt guides to receive the belt supported on the frame with

5 a portion of said loop forming the pivot for mounting the tongue member on the frame and having a second belt-securing loop at the rear end of the tongue member to which the other end of the belt is secured, said loop being positioned 10 on the side of the pivotal mounting opposite the tongue portion and at an angle to the plane of the tongue portion, the tongue moving about the pivotal mounting in the direction of the belt upon a longitudinal pull on the secured end in a direction away from the buckle; and a belt-engaging tooth carried by the end of the tongue portion and adapted to pass through an aperture in the belt and hold the belt when the tongue portion and frame engage the apertured end of the belt.

3. A belt buckle comprising a frame member adapted to underlie the apertured end of a belt and having side bars and a transversely extending member connected to the front ends of the side bars by upwardly extending walls, said walls

15 engaging the side edges of the belt to maintain the belt in position thereon; a tongue member pivotally mounted intermediate its ends on the back end of the frame and having a tongue portion to overlie the belt supported on the frame and having a transversely extending loop forming a belt-receiving passage at the rear end of the tongue portion and in line with the belt guides to receive the belt supported on the frame with a portion of said loop forming the pivot for mount-

20 ing the tongue member on the frame and having a second belt-securing loop at the rear end of the tongue member to which the other end of the belt is secured, said loop being positioned on the side of the pivotal mounting opposite the tongue portion and at an angle to the plane of the tongue

25 portion, the tongue moving about the pivotal mounting in the direction of the belt upon a longitudinal pull on the secured end in a direction away from the buckle; and a belt-engaging tooth carried by the end of the tongue portion and adapted to pass through an aperture in the belt and hold the belt when the tongue portion and frame engage the apertured end of the belt.

4. A belt buckle comprising a frame member adapted to support the apertured end of a belt and including a portion extending transversely of the belt; a tongue member pivotally mounted intermediate its ends on the back end of the frame and having a tongue portion to overlie the belt supported on the frame and having a transversely extending loop forming a belt-

30 receiving passage between the pivotal mounting and the rear end of the tongue portion disposed at an angle to the plane of the tongue portion to receive the belt supported on the frame with a portion of said loop forming the pivot for

35 mounting the tongue member on the frame and having a second belt-securing loop at the rear end of the tongue member to which the other end of the belt is secured, said loop being positioned on the side of the pivotal mounting opposite the tongue portion and at an angle to the plane of the tongue portion, the tongue moving about the pivotal mounting in the direction of the belt upon a longitudinal pull on the secured end in a direc-

tion away from the buckle; and a belt-engaging tooth projecting from the front end of the tongue in the direction of the frame and adapted to pass through an aperture in the belt adjacent the transversely extending portion of the frame and hold the belt when the tongue portion is moved into engagement with the belt.

5. A belt buckle comprising a frame member adapted to support the apertured end of a belt and including a portion extending transversely of the belt; a tongue member pivotally mounted intermediate its ends on the back end of the frame and having a tongue portion to overlie the belt supported on the frame and having a transversely extending loop forming a belt-receiving passage between the pivotal mounting and the rear end of the tongue portion disposed at an angle to the plane of the tongue portion to receive the belt supported on the frame with a portion of said loop forming the pivot for mounting the tongue member on the frame and having a second belt-securing loop at the rear end of the tongue member to which the other end of the belt is secured, said loop being positioned on the side of the pivotal mounting opposite the tongue portion and at an angle to the plane of the tongue portion, the tongue moving about the pivotal mounting in the direction of the belt upon a longitudinal pull on the secured end in a direction away from the buckle; and a belt-engaging tooth projecting from the transversely extending portion in the direction of the tongue portion and adapted to pass through an aperture in the belt to be engaged by the tongue portion and hold the belt when the tongue portion is moved into engagement with the belt.

6. A tongue member for connecting the ends of a belt comprising a narrow tongue portion

adapted to overlie the free apertured end of the belt and having a downwardly extending tooth at its forward end adapted to engage a hole in the belt; a loop at the other end of the tongue extending downwardly therefrom and comprising opposed U-shaped portions projecting beyond the sides of the tongue and adapted to receive the free end of the belt; and a second loop connected to the side of the first loop opposite the tongue portion and extending backwardly therefrom to provide a transverse member to receive and be secured to loop on the other end of the belt.

10. The invention as defined in claim 6 wherein the tooth, tongue portion and two connected loops are comprised of a bent wire member.

15. The invention as defined in claim 6 wherein the tooth, tongue portion and two connected loops are comprised of a unitary stamped sheet metal member.
